US0D1014687S

(12) **United States Design Patent** (10) **Patent No.:** **US D1,014,687 S**
(45) **Date of Patent:** **** Feb. 13, 2024**

(54) **SHADING SYSTEM**

(71) Applicant: **Shibumi Shade, Inc.**, Raleigh, NC (US)

(72) Inventors: **Dane Brooks Barnes**, Raleigh, NC (US); **Alexander Griffith Slater**, Raleigh, NC (US); **Scott Christian Barnes**, Raleigh, NC (US)

(73) Assignee: **Shibumi Shade, Inc.**, Raleigh, NC (US)

(**) Term: **15 Years**

(21) Appl. No.: **29/709,175**

(22) Filed: **Oct. 11, 2019**

Related U.S. Application Data

(63) Continuation of application No. 16/224,465, filed on Dec. 18, 2018, now Pat. No. 10,753,117, which is a continuation of application No. 15/675,715, filed on Aug. 12, 2017, now Pat. No. 10,190,330.

(57) **CLAIM**

The ornamental design for a shading system, as shown and described.

DESCRIPTION

FIG. 1 is a front perspective view of a shading system in an upright position and showing the new design;

FIG. 2 is a front view of the shading system showing the new design;

FIG. 3 is a rear view of the shading system showing the new design;

FIG. 4 is a left side view of the shading system showing the new design;

FIG. 5 is a right side view of the shading system showing the new design;

FIG. 6 is a top plan view of the shading system showing the new design; and,

FIG. 7 is a bottom plan view of the shading system showing the new design.

The dashed lines shown herein depict environmental subject matter or portions of the shading system that form no part of the claimed design.

1 Claim, 7 Drawing Sheets
